Alanson C. Dinn.

Attorney

UNITED STATES PATENT OFFICE.

WILLIAM RING, OF DETROIT, MICHIGAN.

GUARDHOUSE.

Application filed January 3, 1925. Serial No. 410.

To all whom it may concern:

Be it known that I, WILLIAM RING, a citizen of the United States, residing at Detroit, in the county of Wayne and State 5 of Michigan, have invented certain new and useful Improvements in Guardhouses, of which the following is a specification.

This invention relates to a guard house, which is adapted to be placed within a building, such as a jewelry store, bank, hotel or the like, and has for its principal object to provide a bullet-proof enclosure or tower in which is stationed a guard, the guard having a full view of the interior of the part 10 of the building in which the guard house is placed, through suitable port holes arranged in the wall of the tower.

One of the important objects of the present invention is to provide a guard house of 20 the above mentioned character, which has arranged therein suitable means for enabling the guard stationed therein to give a warning signal when a burglar is in the store.

25 A further object is to provide a guard house wherein pivoted closures are associated with the port holes arranged in the walls of the tower comprising the guard house, means being associated with the closures for holding the same in a closed position so that access to the interior of the guard house through the port holes cannot be had, thus entirely protecting the guard stationed therein.

30 A further object is to provide a guard house of the above mentioned character, which is simple in construction, inexpensive, strong and durable, and further well adapted for the purposes for which it is designated.

35 Other objects and advantages of the invention will become apparent during the course of the following description.

In the accompanying drawings, forming a 40 part of this specification, and in which like numerals designate like parts throughout the same:

Figure 1 is a side elevation of the guard house embodying my invention.

45 Figure 2 is a vertical central sectional view taken therethrough, and

Figure 3 is a transverse section, taken approximately on the line 3-3 of Figure 1.

In the drawing, wherein for the purpose 50 of illustration is shown the preferred embodiment of my invention, the numeral 1

designates generally my improved guard house, the same comprising the substantially cylindrical tower, the top and bottom thereof of being closed, as illustrated at 3 and 4 60 respectively. The tower is constructed of suitable bullet proof material, and a door, such as is illustrated at 5, is associated with the tower, whereby access to the interior thereof may be had. The door is located in 65 the wall of the tower, adjacent the lower portion thereof.

A lock of any conventional construction is associated with the door so that when the tower is occupied, the door may be locked 70 by the person on the inside, so that access to the interior of the tower from the outside cannot be had.

Arranged in spaced relation in the upper portion of the circular wall of the tower 2 75 are a plurality of port holes, indicated at 6. A pivoted closure is associated with each of the port holes, and the same comprises a metallic plate, the intermediate portion 7 thereof being disposed within the opening 6, the ends of the intermediate portion 7 being seated in suitable notches provided therefor and indicated at 8, whereby the intermediate portion 7 of each closure is adapted for pivotal swinging movement.

The outer portion of each of the closures is disposed downwardly as illustrated at 9, adjacent the outside of the cylindrical wall of the tower, while the inner portion of each of the closures is disposed upwardly on the 80 inside of the tower, as illustrated at 10. It is obvious that when the inner portion of the closure plate is swung downwardly, so that the intermediate portion 7 will be disposed in a substantially horizontal plane, the 85 guard stationed within the tower may view the interior of the store or the like in which the tower is placed, through the port hole.

For the purpose of normally holding the pivoted closure plate in a closed position 100 with respect to the port holes, each is provided with a short piece of chain 11, at its upper inner end 10, for cooperation with a hook 12, secured on the inner wall of the tower 2, directly above each of the port holes. 105 This construction is more clearly illustrated in Figure 2.

A table, of any conventional construction, is placed within the tower, and supports a telephone and a switch box 13 and 14 respectively. The wiring from the telephone and switch box stands upwardly through the 110

top 3 of the tower as clearly illustrated in Figure 2.

Also provided in the top 3 of the tower are the ventilating openings 15.

5 When a burglar enters a jewelry store, bank or the like, in which is placed the tower, the guard stationed within the tower may view the burglar through one of the port holes, and immediately give a warning, 10 through the use of either the telephone or the switch box 14, which may be connected with the central police station or the like, thus enabling sufficient help to be called to the store and prevent the burglar from escaping or obtaining anything of value from the store or its occupants. The guard within 15 the guard house cannot be seen by the burglar, and furthermore, by constructing the guard house of bullet proof material, the 20 guard is protected against any possibility of injury, should the burglar fire upon the guard house. The port holes in the tower are of such size as to permit a barrel of a gun to be placed therethrough, when the 25 guard finds it necessary to fire upon the burglar.

The simplicity of my device enables the same to be constructed at a very low cost, and will at all times, be strong and durable.

30 While I have shown the preferred embodiment of my invention, it is to be understood that various changes in the size, shape, and arrangement of parts may be resorted to, without departing from the spirit of the invention or the scope of the appended claims.

Having thus described my invention, what I claim as new is:

1. A guard house comprising a substantially cylindrical tower of bullet proof material, and closed at its respective ends, a

door in the wall of the tower whereby access to the interior thereof may be had, said tower having a plurality of port holes formed in the wall thereof at spaced intervals, and a closure for each port hole, the 45 same comprising a plate, the intermediate portion thereof being disposed within the port hole, the ends of the intermediate portion of the plate being disposed in notches formed in the respective ends of the port hole to facilitate the swinging movement of the plate the outer portions of each plate being disposed downwardly on the outside of the wall of the tower, the inner portion of each plate being disposed upwardly adjacent the inner wall of the tower. 50

2. A guard plate comprising a substantially cylindrical tower of bullet proof material, and closed at its respective ends, a door in the wall of the tower whereby access to the interior thereof may be had, said tower having a plurality of port holes formed in the wall thereof at spaced intervals, a closure for each port hole, the same comprising a plate, the intermediate portion thereof being disposed within the port hole, the ends 60 of the intermediate portion of the plate being disposed in notches formed in the respective ends of the port hole to facilitate the swinging movement of the plate, the outer portions of each plate being disposed downwardly on the outside of the wall of the tower, the inner portion of each plate being disposed upwardly adjacent the inner wall 65 of the tower, and means associated with the inner portions of the closure plate and the inner wall of the tower for locking the closure plate in a closed position. 70

In testimony whereof I affix my signature.

WILLIAM RING.
